(57) **CLAIM**

The ornamental design for a buckle, as shown and described.

DESCRIPTION

FIG. 1 is an exploded perspective view of a buckle, showing my new design;

FIG. 2 is an exploded front elevation view thereof;

FIG. 3 is an exploded rear elevation view thereof;

FIG. 4 is an exploded left side elevation view thereof;

FIG. 5 is an exploded right side elevation view thereof;

FIG. 6 is a top plan view thereof;

FIG. 7 is a bottom plan view thereof;

FIG. 8 is a perspective view thereof, wherein the top and bottom panels are shown in a used condition connected;

FIG. 9 is another perspective view of FIG. 8, wherein the buckle is attached to a first configuration of straps shown in broken lines; and,

FIG. 10 is another perspective view of FIG. 8, wherein the buckle is attached to a second configuration of straps shown in broken lines.

The broken lines of FIG. 9 and FIG. 10 depicting straps represent environmental structure that forms no part of the claimed design. The remainder of the broken lines depict portions of the buckle that form no part of the claimed design.

1 Claim, 10 Drawing Sheets
